(No Model.)

R. W. PAIN.
MUSICAL INSTRUMENT.

No. 417,680.

Patented Dec. 17, 1889.

Fig.1

UNITED STATES PATENT OFFICE.

ROBERT W. PAIN, OF NEW YORK, N. Y.

MUSICAL INSTRUMENT.

SPECIFICATION forming part of Letters Patent No. 417,680, dated December 17, 1889.

Application filed May 6, 1889. Serial No. 309,804. (No model.)

To all whom it may concern:

Be it known that I, ROBERT W. PAIN, of New York, in the county and State of New York, have invented a certain new and useful Improvement in Musical Instruments, of which the following is a specification.

My improvement relates especially to piano-fortes operated mechanically.

In the accompanying drawings, Figure 1 is a front view of a musical instrument embodying my improvement, the front of the case being removed and certain of the parts being omitted. Fig. 2 is a vertical section of a portion of this instrument upon a larger scale, the plan of the section being transverse to the length of the instrument.

Similar letters of reference designate corresponding parts in both figures.

A designates the strings of a piano-forte.

B designates hammers for operating upon the strings.

C designates rods serving to actuate the hammers. These rods C are moved upwardly by keys D, of ordinary construction, fulcrumed between their ends upon a rail D' and held in position by pins D''. These keys are for operating the instrument manually.

G designates a number of electro-magnets. Their armatures G' are carried by levers F, that are fulcrumed between their ends, and at the rear ends serve to transmit motion through pins E to the keys D for the purpose of operating the hammers. There is one of these electro-magnets for each note to be sounded. Each electro-magnet G is connected by electric-circuit wires W' W² W³ W⁴ with contact-pieces P' P². The connections between the electro-magnets and the contact-pieces are in multiple arc and the main-circuit wires are

in communication with a battery W⁵. There is one contact-piece P' for each electro-magnet G. The contact-piece P² is, however, common to all the electro-magnets. As here shown, a wire W³ extends from one pole of the battery W⁵ to a metal brush P⁴, impinging upon a journal of the contact-piece P². A wire W⁴ extends from the other pole of the battery to the coils of the electro-magnets G. From the coils of the electro-magnet G a number of wires W² extend to the contact-pieces P'. These wires may advantageously be offset into a cable from a point somewhere about

the point W', Fig. 2, to a point near the magnets G. The contact-pieces P' are pressed into contact with the contact-piece P² by means of pneumatic motors J, arranged in a chamber I. This instrument is intended to operate in connection with exhaust-bellows O²; hence this chamber I is an exhaust-chamber. Internally the pneumatic motors J communicate through ducts a and pipes a' with the ducts a² of the tracker or rest K. A perforated music-sheet L passes over this tracker or rest and controls the admission of air to the motors. When the motors are expanded by the entrance of air, their movable boards operate through pins P³, extending through the bottom of the chamber I to the contact-pieces P', to press the contact-pieces P' down upon the contact-piece P², thus completing the circuits in which the magnets G are arranged and causing the latter to oscillate the levers F and keys D in such way as to effect the operation of the hammers.

The bellows O² are operated by an electro-magnetic engine Q through a belt R, transmitting motion to a crank-shaft O³, connected by pitman O⁴ to the bellows O². A wire W⁷ extends from the battery W⁵ to one of the binding-posts of this engine. The other binding-post of the engine is connected by a wire with a switch-lever W⁸. A wire W⁶ extends from the battery W⁵ to a contact-piece s⁵, with which the switch-lever co-operates.

S designates resistance-coils connected to a number of contact-pieces s⁴ s³ s² s'. The switch-lever may be adjusted into contact with any of the contact-pieces s' s² s³ s⁴ s⁵, to introduce more or less resistance into the circuit of the engine Q, for the purpose of the latter.

The bellows O² communicate with an equalizer O'. This is connected by a pipe O⁵ with a chamber I', which communicates with the chamber I, under control of a valve I². The valve I² is connected with mechanism for reversing the music-sheet, so as to effect the rewinding of it. Whenever the mechanism is reversed, so as to effect the rewinding of the music-sheet, the valve I² is shifted, so as to cut off communication between the bellows and the chamber I and render the pneumatic motors J inoperative. Thus the speaking of the sound-producing devices during the re-

winding of the music-sheet will be prevented. The equalizer O' is also connected by a pipe O with a wind-motor consisting of a number of bellows-like chambers M and a crank-shaft N, connected to their movable boards. The crank-shaft N of the wind-motor transmits motion through a belt N' to a shaft N², serving to impart motion to the music-sheet. A valve O⁶ serves to control the passage of air through the pipe O, and so regulate the speed of the motor.

- My present improvement resides in the contact-piece P². This consists of a cylinder made of or faced with metal. In the present instance it is represented as made of metal and journaled in bearings P⁵, affixed to the under side of the chamber I. When made of metal, the brush P⁴ may impinge upon one of its journals. Rotary motion is imparted to this contact-piece P² by means of a belt P⁶, receiving motion from a pulley on the shaft N² and transmitting motion through a pulley affixed to one of the journals of said contact-piece.
- I have found that by this improvement I can maintain a uniformity of action in a mechanical musical instrument and avoid the tendency to fuse and adhere by sparking when separating the contact-pieces. The contact-pieces are not apt to stick together or become liable to damaging sparking.

What I claim as my invention, and desire to secure by Letters Patent, is—

1. In a mechanical musical instrument, the combination of a number of electro-magnets for causing the operation of sound-producing devices, electric circuits or branch circuits comprising these electro-magnets, a number of contact-pieces corresponding to the number of magnets, pneumatic motors for operating these contact-pieces, a music-sheet controlling the pneumatic motors, a contact-piece

opposite the contact-pieces aforesaid and consisting of a rotary cylinder, and mechanism, substantially such as described, for rotating the said cylinder, substantially as specified. 45

2. In a mechanical musical instrument, the combination of a number of electro-magnets for causing the operation of sound-producing devices, electric circuits or branch circuits comprising these electro-magnets, a number of contact-pieces corresponding to the number of magnets, pneumatic motors for operating these contact-pieces, a music-sheet 50 controlling the pneumatic motors, a contact-piece opposite the contact-pieces aforesaid and consisting of a rotary cylinder, mechanism, substantially such as described, for rotating the said cylinder, and a metal brush 55 impinging upon said cylinder, substantially as specified.

3. In a mechanical musical instrument, the combination of a number of electro-magnets for causing the operation of sound-producing devices, electric circuits or branch circuits comprising these electro-magnets, a number of contact-pieces corresponding to the number of magnets, pneumatic motors for operating these contact-pieces, a music-sheet 60 controlling these pneumatic motors, rollers upon which the music-sheet is wound and rewound in reverse directions, a valve operated when the music-sheet is moved backward to render the pneumatic motors inoperative, a rotary cylinder forming a contact-piece and arranged opposite the contact-pieces aforesaid, and mechanism, substantially such as described, for rotating this cylinder, substantially as specified. 70
